UNITED STATES PATENT OFFICE.

ALEXANDER W. WADERLOW, OF DETROIT, MICHIGAN.

COLLAPSIBLE STOOL.

Application filed April 22, 1921. Serial No. 463,445.

To all whom it may concern:

Be it known that I, ALEXANDER W. WADERLOW, a subject of the King of Great Britain, residing at Detroit, in the county of Wayne 5 and State of Michigan, have invented certain new and useful Improvements in Collapsible Stools, of which the following is a specification, reference being had therein to the accompanying drawings.

10 In my Patent No. 1,365,873, granted Jan. 18, 1921, there is disclosed a collapsible stool seat provided with an adjustable telescopic pedestal and legs that may be housed within the pedestal, the legs when in an active position having a tripod formation at the base of the pedestal with a detachable retaining member holding the legs distended. This same detachable retaining member is employed for retaining the legs 15 within the pedestal when the stool is not in use and by reason of the pedestal being constantly held at a right angle to the lower face of the stool seat, the stool will occupy considerable space unless the pedestal is detached.

20

25

This invention relates to certain improvement in connection with my former collapsible stool and the improvements may be characterized as follows;

30 First, there is a telescopic pedestal which may be extended to accommodate the legs of the stool and retracted to provide a comparatively short pedestal for the stool when in an active position. In making the pedestal telescopic and pivotally mounting it 35 on the lower face of the seat, it is possible to place the extended pedestal and its legs in parallelism with the stool seat, so that the collapsed stool will occupy comparatively small space in being carried or in 40 storage. In being able to shorten the length of the pedestal a comparatively low and substantial stool structure is obtained which may be advantageously used in automobiles 45 or other vehicles for carrying extra passengers.

Another feature of the present invention is a leg supporting head which is devoid of detachable parts, for instance, the detachable retaining member disclosed in my prior 50 patent. The leg supporting head, in this invention, has novel means for retaining the tripod legs of the stool extended or retracted, and with such means constantly in 55 engagement with the leg supporting head

there is no danger of parts becoming displaced or lost during the use of the stool.

Other features of my invention will hereinafter appear and reference will now be had to the drawing, wherein—

60 Figure 1 is a side elevation of the stool in an active position;

Fig. 2 is an enlarged vertical sectional view of a portion of the stool seat showing a portion of the telescopic pedestal 65 therein;

Fig. 3 is a vertical sectional view of the lower portion of the collapsible stool, showing the legs thereof distended;

Fig. 4 is a cross sectional view taken on 70 the line IV—IV of Fig. 2, looking towards the stool seat;

Fig. 5 is a bottom plan of the leg supporting head shown in Fig. 3;

Fig. 6 is a side elevation of a portion of 75 the stool showing the pedestal in parallelism with the stool seat, and

Fig. 7 is a bottom plan of the stool seat showing the legs within the pedestal and the pedestal in parallelism with the stool 80 seat.

In the drawings, the reference numeral 1 denotes the stool seat, preferably circular in plan and made of one or more pieces of wood or durable material. The lower face 85 of this stool seat is provided with a centrally located socket plate 3, preferably triangular in plan and connected to the stool seat by screws 2 or other fastening means. That face of the socket plate 3 confronting 90 the stool seat 1 is provided with a cylindrical socket 4 extending into a recess 5 provided therefor in the stool seat 1, and the outer face of the socket plate has opposed lugs 6 and 7 connected by a semi-circular enlargement 8 on the socket plate 3, said enlargement serving as a stop for the pedestal when swinging the pedestal from an inactive position to an active position.

100 The lug 7 is provided with an opening 9 and the lug 6 with a recess 10. Communicating with the inner end of the opening 9 is a longitudinally disposed slot 11 extending into the socket 4, and said socket has an annular seat 12 for the upper end of the telescopic pedestal, which consists of an outer tubular member 13 and an inner tubular member 14. The upper end of the outer tubular member 13 is adapted to engage the 110

seat 12 when in an active position, and said tubular member has one wall thereof provided with a stud 15 held by a rivet 16, said stud extending into the slot 11 and, at times, 5 extending axially of the opening 9 of the lug 7. The opposite wall of the outer member 13 has spaced openings 17 and 18 connected by a longitudinal slot 19 and adapted to extend into either of the openings 17 10 and 18 is a conical shaped latch 21 slideable in the recess 10 of the lug 6, said latch having a stem 22 extending axially of the recess 10 and out of the lug 6 where it is provided with a suitable hand piece 23. In the recess 15 10, about the stem 22, is a coiled compression spring 24 and the expansive force of this spring against the latch 21 is adapted to normally hold said latch in either of the openings 17 or 18, depending on the position 20 of the outer tubular member 13 relative to the socket 4.

The lower end of the outer tubular member 13 is provided with a frusto-conical shaped leg supporting head 25 having a plurality of radially disposed openings 26 communicating with the interior of the tubular outer member 13. In the openings 26 are placed legs 27 that may be shifted into the telescopic pedestal when the same is distended, as shown in Fig. 7. Each of the 30 legs 26 is preferably in the form of a rod having a conical inner end 28 provided with a transverse pin 29 and an annular groove 30. The outer end of each leg has an annular groove 31 and an angularly disposed floor or ground engaging face 32. The conical inner ends 28 of the legs 27 permit of the inner ends of the legs being clustered or closely assembled so that said legs may bear 35 against angularly disposed walls 33 of the openings 26 and the angularity of the walls 33 determine the angle of the legs 27 relative to the longitudinal axis of the pedestal.

The transverse pins 29 serve two purposes 40 in connection with the legs 27. First, said pins will prevent rotation of the legs 27 and at all times maintain the faces 32 correctly positioned to engage a floor or the ground. Second, the pins 29 will prevent the legs 27 45 from falling out of the leg supporting head 25, but other devices are also employed for this purpose, as will now be described.

Protruding into each one of the openings 50 26 is a spring pressed detent 34 preferably in the form of a ball yieldably mounted in a socket or recess 35 horizontally disposed within the leg supporting head 25. Each detent is pressed by a spring 36 retained within the socket 35 by a countersunk screw 60 plug 37, and each detent serves two purposes. First, the detents are adapted to engage in the grooves 31 at the outer ends of the legs 27 and retain said legs within the telescopic pedestal, as shown in Fig. 7. Second, the location of the detents 34 is such that said de-

tents may cooperate with the transverse pins 29 in retaining the legs 27 against the angularly disposed walls 33 of the openings 26. It is therefore possible to place the legs 27 in a tripod formation relative to the leg supporting head 25 without any danger of said legs swinging downwardly into a vertical position, which they would surely do with the stool off of its support, and if some means were not provided for holding the legs in proper relation to the telescopic pedestal so that the stool could be easily placed on its support.

Cooperating with the leg supporting head 25 for holding the legs 27 extended and in an active position are spring pressed keepers 38 arranged in sockets 39 and protruding into the openings 26, so that said keepers may engage in the annular grooves 30 of the legs 27 and hold the legs in set positions.

The inner tubular member 14 has its lower end opened to receive the legs 27 and the upper or inner end of the member 14 is closed by an end cap 40. When the legs 27 impinge against the end cap 40, the inner member 14 may be shifted relative to the outer member 13 so that the telescopic pedestal may accommodate the legs 27 as shown in Fig. 7, and the inner member 14 90 may be gripped and shifted into the outer member 13 to assist in distending the legs 27 relative to the legs supporting head 25. To prevent the inner member 14 from rotating relative to the outer member 13, said inner member has a longitudinal depression or groove 41 to receive the rivet 16 of the stud 15.

Considering the pedestal connection with the socket 4, it will be noted by reference to Fig. 2 that the latch 21 retains the outer member 13 on the seat 12 within the socket 4 and that the stud 15 extends into the slot 11 of the socket. The outer member 13 may be pulled outwardly until the latch 21 engages in the opening 18 of the outer member, at which time the stud 15 alines with the opening 9 and the outer member 13 may be swung toward the lower face of the seat 1 to assume a position practically in parallelism therewith, for instance, as shown in Figs. 6 and 7. With the outer member 13 in this position the legs 27 may be pushed into the inner member 14 and said member extended relative to the outer member 13. 110 The telescopic pedestal will therefore be held at its middle portion and cannot swing to a vertical position until the telescopic pedestal is collapsed.

Again referring to Fig. 2, it will be noted that the seat 12 and the walls of the socket 4 retain the outer member 13 at a right angle to the seat 1 so that the upper end of the pedestal will be rigidly held while the seat is being occupied. Since the legs 27 are 120 130

firmly held by the head 25, the stool may be safely used and by reason of its short pedestal it may be placed on the floor of an automobile body to afford an additional seat 5 for an extra passenger. The stool is collapsible and may be easily carried under one of the automobile seats or placed in the automobile kit so as to be convenient for increasing the carrying capacity of an automobile without any great discomfort to 10 other occupants of the machine.

One embodiment of my invention has been illustrated, but it is to be understood that the structural elements are susceptible to 15 such variations and modifications as fall within the scope of the appended claims.

What I claim is:—

1. A stool having a seat, a pedestal outer member constantly connected to said seat 20 and swingable into parallelism with said seat and with its outer end terminating approximately at the edge of said seat, an inner member in said outer member extensible relative to said outer member only when

said outer member is parallel to said seat, 25 and legs for said outer member adapted to be housed by said inner and outer members.

2. A stool as in claim 1, and means carried by said outer member adapted to hold the legs in adjusted positions relative to 30 said inner and outer members.

3. A stool comprising a seat, a pedestal, legs carried thereby, said pedestal being of greater length when inactive relative to said seat than when active, and which legs when 35 active are extended relative to said pedestal, and when inactive housed within said pedestal.

4. A stool as in claim 3, wherein said pedestal when inactive is disposed in parallelism with said seat. 40

In testimony whereof I affix my signature in presence of two witnesses.

ALEXANDER W. WADERLOW.
